UNITED STATES PATENT OFFICE.

JOHN M. MARLIN, OF NEW HAVEN, CONNECTICUT.

MAGAZINE FIRE-ARM.

SPECIFICATION forming part of Letters Patent No. 413,196, dated October 22, 1889.

Application filed November 28, 1884. Serial No. 148,992. (No model.)

To all whom it may concern:

Be it known that I, JOHN M. MARLIN, of New Haven, in the county of New Haven and State of Connecticut, have invented a certain 5 new and useful Improvement in Magazine Fire-Arms, of which the following is a specification.

My invention relates to magazine fire-arms; and it consists in certain improvements in 10 the magazine and connections therewith, substantially as hereinafter described and claimed.

In the drawings, Figure 1 is a side view of the barrel and magazine of a fire-arm, partly 15 in section. Fig. 2 is a view of the magazine and magazine-case detached from the arm, partly in section, and broken away to show the internal construction. Fig. 3 is a view of the muzzle end of the arm with the magazine 20 inserted in its case before it is locked. Fig. 4 is a side view of the same from one direction. Fig. 5 is a side view of same from another direction. Fig. 6 is a side view of the same after the magazine has been turned and 25 locked in its case. Fig. 7 is an end view of same. Fig. 8 is a section through the line A-A of Fig. 1. Fig. 9 is a side view in section of a portion of Fig. 1 from a different direction than is shown in that figure.

My present invention is an improvement 30 upon the mechanism shown in my application filed in the Patent Office August 4, 1884, No. 139,587.

B is the barrel of the arm.

C is the magazine-case.

D is the magazine, which is removable from the case to fill the same with cartridges. This magazine is constructed to be filled and inserted in the case and revolved a part of a 35 turn, which unlocks the sliding bolt d from the notch d' by bringing the head of the bolt d against the inward projection d² in the magazine-case, and allows the bolt d to slide along the groove d³, substantially as described 40 in my former application. This allows the spiral spring d⁴ to force the bolt d against the cartridges and force them from the magazine in the ordinary manner.

In order to prevent the cartridges from escaping from the magazine before it is seated 45 in its bearings in the magazine-case and while it is being introduced therein, I provide

a sliding sleeve e on the end of the magazine, to which is attached a spring e', which projects through a slot into the magazine when 50 the sleeve e is shoved toward the open end of the former, as shown in Fig. 9, and in this position the end of the spring forms a stop to prevent the cartridges from escaping. When the magazine is pressed downward into its 55 case, as shown in Fig. 1, the shoulder e² comes against the end of the sleeve e and crowds it toward the muzzle of the arm, thus withdrawing the spring e' from the magazine and allowing the cartridge to escape from the open 60 end thereof.

In order to lock the magazine in place when it is revolved so as to bring its head c into the groove c', as described in my said former application, I provide a latch c², which is pivoted in the head end of the magazine, as 65 shown in Fig. 2, upon a pivot c³, passing through a slot c⁴ in the latch, and the latch is held outward by a spiral spring c⁵. I next provide in the magazine-case C at the muzzle 70 end of the arm an L-shaped slot m, so constructed that when the magazine is first inserted into the case the latch c² will enter this slot in the position shown in Figs. 3, 4, and 5, and be crowded inward upon the spiral 75 spring c⁵; but when the magazine is turned to the position shown in Figs. 6 and 7 the shoulder c⁶ upon the latch c² will be pressed by the spiral spring c⁵ outward into the horizontal part of the L-shaped slot m, as shown 80 in the last-named figures, and will thus prevent the magazine from being revolved backward so as to release its head c from the slot in the barrel c' by any accident.

When it is desired to remove the magazine 85 from its case, by simply pressing inward with the thumb upon the projecting part of the latch c² until the shoulder c⁶ is withdrawn from the L-shaped slot the magazine may be revolved backward until its head is released 90 from the slot c', when it can be withdrawn from its case.

It will be observed that the spring-stop e' and the latch c² automatically operate in conjunction and by the same movements of the 95 magazine in inserting it into its case, and when the magazine is locked in place at the muzzle end of the arm, as described, the spring-stop e' is thereby prevented from en-

tering the bore of the magazine by any accident. It will also be observed that the same movements which automatically lock the magazine in place by the latch c^2 unlock the bolt d from the notch d' automatically.

What I claim as new and of my invention is—

1. The combination of the removable magazine D, the sleeve e , having stop e' attached thereto, and the shoulder e^2 , located in the magazine-case C in the path of sleeve e when the magazine is introduced into the case, and adapted to be brought into contact with and move the sleeve and stop when the magazine is inserted in its case, substantially as described.

2. The combination of the removable magazine D, provided with the latch c^2 , attached thereto, and the head c , projecting laterally therefrom, with the magazine-case provided with the slot m , and the barrel of the arm, provided with the slot c' , said slots m and c' being respectively located and adapted to engage with said latch and head of the magazine, substantially as described.

3. The combination of the magazine-case C, provided with the slot m and stop d^2 , projecting inwardly, the removable magazine D, fitting within the case and provided with the slot d^4 and stop-notch d' , the spring d^3 and the sliding bolt d within the magazine, provided with a head adapted to engage with notch d' to lock the same and with stop d^2 to unlock the same, and the latch c^2 , adapted to lock said magazine and its case together, substantially as described.

4. The combination of the magazine-case C, provided with the shoulder e^2 and slot m , with the removable magazine D, provided with the sliding sleeve e , adapted to engage with said shoulder and the stop e' , and the latch c^2 , adapted to lock said magazine and case together by engaging slot m , substantially as described.

JOHN M. MARLIN.
